CLAIM

The ornamental design for a makeup mirror, as shown and described.

DESCRIPTION

FIG. 1 is a front perspective view of a makeup mirror showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof, shown in an open position of use.

The broken lines are shown for the purpose of illustrating parts of the article that form no part of the claim.
